UNITED STATES PATENT OFFICE.

HENRY AUGUST PREUSS, OF HAMBURG, GERMANY, ASSIGNOR OF FORTY ONE-HUNDREDTHS TO FRANCISCO VILMAR, OF RIO DE JANEIRO, BRAZIL.

CLUTCH MECHANISM FOR PHONOGRAHS.

1,145,793.

Specification of Letters Patent.

Patented July 6, 1915.

Application filed January 28, 1914. Serial No. 815,056.

To all whom it may concern:

Be it known that I, HENRY AUGUST PREUSS, a citizen and resident of Hamburg, Germany, have invented a new and useful 5 Clutch Mechanism for Phonographs, of which the following is a specification.

The present invention relates to a device for starting a gramophone, which operates in connection with an automatic piano or an 10 other instrument or the like. In apparatus of this description it is of great importance that the gramophone should commence at normal running speed so as to secure accurate agreement of the singing or speaking 15 of the gramophone with the accompaniment of the piano. Heretofore it has been found very inconvenient, that the gramophones always start slowly and that the desired speed is not attained until a certain space of time 20 has lapsed. For this reason there is a long dummy line in the beginning of the record or phonic line of the gramophone disk, but it is found very difficult in allowing the gramophone to play together with other instruments to make use of this foreline in 25 such manner, that the reproduction commences at the proper moment. This difficulty is completely done away with by the present invention. The carrier for the record plate is not directly attached to the driving shaft, but is brought in operative connection therewith, when the shaft has obtained the requisite speed, while contrary 30 to the arrangements known heretofore the driving mechanism when starting to run is 35 out of connection with the record carrier, but secures a proper and instantaneous starting of the carrier at the desired moment.

With this object in view the carrier disk 40 for the record plate is attached to a hollow boss or socket movable in a longitudinal direction, carrying at its lower end a special coupling disk and adapted to be slid on the driving shaft. The counter coupling disk is 45 attached to the driving shaft and the first named coupling disk can be raised together with the hollow boss and the carrier for the record plate. When these devices forming together a coherent body are lowered which 50 should be done not before the shaft has attained its full speed, the record plate will start at once with its requisite speed. In combination with this device special lifting means will be employed for raising the said 55 coherent body. In its raised position the

lifting piece, which is acted upon by a spring is held by a pawl, which at proper time releases the lifting piece and allows the said body to quickly descend. If so desired the pawl may be brought in connection with a pneumatic or other moving means to allow the release to take place automatically or from any desired distance. 60

Figure 1 of the drawing is a vertical section, and Fig. 2 a plan of the apparatus. 65 Fig. 3 is a detail of the apparatus in elevation, and Fig. 4 a plan of the record plate. Fig. 5 is a similar view to Fig. 1, showing a modification of the device shown in Fig. 3.

In the top plate *a* of the gramophone casing or cover of an automatic piano or the like a vertical boss *b* is journaled to which a coupling disk *c* is attached at its lower end and the carrier disk *d* for the record plate *e* at its upper end. The boss *b* is hollow at its lower end to receive the top of the driving shaft *f*. The upper end *g* of the shaft *f* is reduced in its diameter forming a shoulder *h*, the uppermost end of the reduced end *g* being pointed. The bore of the boss *b* is similarly shaped thus securing a good guide of the boss on the uppermost end of the shaft *f* as well as on a point somewhat lower down that is to say on the shoulder *h*. To the shaft *f* the counter coupling disk *i* 70 is firmly attached and the upper surface of this disk is provided with cloth or fabric to increase the friction when contacting with the disk *c*. This last named disk is provided with cloth on its lower surface as well as on the upper surface, and also the top *a* is on its lower surface provided with cloth or other fabric. When the disk *c* is in its upper position (as shown in Fig. 1) it is held 75 against rotation but it will rotate at the speed of the shaft *f* when lowered so as to allow the disk *c* to contact with the disk *i* which at once carries it around. 80

The disks *d* and *e* together with the shaft *b* and disk *c* are held in their upper position by a lifting piece *k* arranged on the lever *m* pivoted to the cover *a* by the pin *m'*. The lifting piece *k* is preferably bifurcated, and the prongs *k'* thereof have a sloping surface to engage rollers *o* attached to the 95 free end of a spring arm *p* secured at its opposite end *2* to the casing *a*. The arm *p* is further provided with an opening 3 through which the boss *b* projects and forms a guide about which the arm is moved, the 100 105 110

latter normally engaging a shoulder b^1 of the body c, b, d . The spring normally tends to keep the table d raised, but is of a strength inferior to the weight of the same so as not to interfere with the descent of the table. In descending, however, the spring p exercises a cushioning effect on the table, and in raising assists the table to respond readily to the application of the cams k^1 . The lever m is provided with a handle m^1 to move the same, when the lifting piece k is to be moved so as to catch below the rollers and to raise the coupling disk c from the counter coupling disk i . The coupling disk c is held in this raised position by the lifting piece k , the lever m carrying the lifting piece k being held itself in this position by a pawl q which is also provided with a handle in such manner, that by depressing the handle q^1 the release is effected. The pawl q is acted upon by a spring r to prevent an untimely release.

In the modification shown in Fig. 5 the pawl q is brought in connection with an automatic releasing piece consisting of a small cylinder s and piston t connected with the prolongation q^2 of the pawl q by a lateral arm. When air is sucked out of the cylinder s for instance, when a perforation in the music band of an automatic piano passes the tracker board, as is well known in instruments of this description and therefore needs no special illustration, the piston t is moved downward. Such movement will be transmitted to the pawl q in such manner as to release the lever m and the spring n will consequently move the lever m in such manner as to withdraw the lifting piece k from under the rollers o . At the same time the boss or shaft b together with a carrier disk d and coupling disk c is lowered and the latter will at once be taken around by the counter coupling disk i and the reproduction of the gramophone will at once commence. Should it be desired to make use of air pressure in the pneumatic cylinder instead of sucking air from the same, the pawl q will have to be so arranged as to engage the lever m from below instead of from above.

In producing the record plate e , Fig. 4, that is to say in recording the usual fore-line will be omitted. It is however preferable to make use of a small notch v which is connected with the record line x by a short but suitably deep furrow. This notch v together with the furrow w serves for properly positioning the needle when starting the gramophone.

I claim:

1. In a device of the character described, the combination of a casing, a continuously-driven shaft journaled vertically in said casing, a clutch element mounted to rotate with said shaft, a second clutch element ar-

ranged to coöperate with said first-named element, a stub shaft carrying said second clutch element journaled for vertical movement in said casing coaxial with said first-named shaft and adapted to descend by gravity to permit engagement of said clutch elements, and means for raising said stub shaft to disengage said clutch elements comprising a projection associated with said stub shaft, a lever pivoted on said casing, and a cam secured to said lever and adapted to engage said projection when the lever is moved and raise said stub shaft. 70

2. In a device of the character described, the combination of a casing, a continuously-driven shaft journaled vertically in said casing, a clutch element mounted to rotate with said shaft, a second clutch element arranged to coöperate with said first-named element, a stub shaft carrying said second clutch element journaled for vertical movement in said casing coaxial with said first-named shaft and adapted to descend by gravity to permit engagement of said clutch elements, and means for raising said stub shaft to disengage said clutch elements comprising a pair of rollers associated with said stub shaft, a lever pivoted to said casing, and a pair of cams secured to said lever and adapted to engage said pair of rollers when the lever is moved and raise said stub shaft. 80

3. In a device of the character described, the combination of a casing, a continuously-driven shaft journaled vertically in said casing, a clutch element mounted to rotate with said shaft, a second clutch element arranged to coöperate with said first-named element, a stub shaft carrying said second clutch element journaled for vertical movement in said casing coaxial with said first-named shaft and adapted to descend by gravity to permit engagement of said clutch elements comprising a spring associated with said stub shaft and arranged to be compressed when said shaft descends, a pair of rollers projecting from said spring, a lever pivoted to said casing, and a pair of cams secured to said lever and adapted to engage said pair of rollers when the lever is moved and raise said stub shaft. 100

4. In a device of the character described, the combination of a casing, a continuously-driven shaft journaled vertically in said casing, a clutch element mounted to rotate with said shaft, a second clutch element arranged to coöperate with said first-named element, a stub shaft carrying said second clutch element journaled for vertical movement in said casing coaxial with said first-named shaft and adapted to descend by gravity to permit engagement of said clutch elements, a spring associated with said stub shaft and arranged to be compressed when said shaft descends, a pair of rollers project- 110

ing from said spring, a lever pivoted to said casing, a pair of cams secured to said lever and adapted to engage said pair of rollers when the lever is moved and raise said stub shaft to disengage said clutch elements, a spring for moving said lever to disengage said cams and rollers and permit the stub shaft to descend, and means for yieldingly confining said lever in position to engage 10 said cams and rollers.

5. In a device of the character described, the combination of a casing, a continuously rotating drive shaft journaled vertically in said casing, a clutch element mounted to 15 rotate with said drive shaft, a stub shaft journaled for vertical movement in the top of said casing and in axial alinement with said drive shaft, a clutch element mounted to rotate with said stub shaft, a flat spring 20 secured at one end to the upper face of said casing and provided at its free end with a perforation for engaging over said stub shaft, a removable element mounted on said stub shaft and providing therewith a shoulder 25 der against which the free end of said spring is adapted to abut, a pair of rollers projecting in a horizontal plane from diametrically opposite points of said spring, a lever pivoted on the top of said casing for 30 horizontal movement, a bifurcated block secured to said lever, a cam mounted on each fork of said bifurcated block and arranged to engage said rollers when the lever is moved in one direction whereby to raise 35 said stub shaft and disengage said clutch elements, a spring normally tending to move said lever to disengage said cams and rollers and permit the stub shaft to descend and engage 40 said clutch elements, and means for holding said lever in the position to effect engagement of said cams and rollers, substantially as described.

6. In a device of the character described, the combination of a casing, a continuously

rotating drive shaft journaled vertically in 45 said casing, a clutch element mounted to rotate with said drive shaft, a stub shaft journaled for vertical movement in the top of said casing and in axial alinement with the drive shaft, a second clutch element carried by said stub shaft and arranged to engage said first-named clutch element when the stub shaft is moved in one direction, a flat spring mounted at one end in the upper 50 face of said casing and provided at its free end with an elongated perforation arranged to engage over said stub shaft, a phonographic table removably mounted on said stub shaft and forming therewith a shoulder against which the flat spring is adapted to 55 abut, a pair of rollers mounted on the free end of said flat spring and projecting at substantially diametrically opposite points with respect to the stub shaft, a lever pivoted on the top of said casing for horizontal 60 movement, a bifurcated block carried by said lever, a cam mounted on each fork of said bifurcated block and arranged to engage the rollers projecting from said flat 65 spring whereby to raise said stub shaft and disconnect the clutch elements, a coil spring mounted on the top of said casing and adapted to normally move said lever to disengage 70 said cams and rollers and permit the stub shaft to descend, a slotted guide for said lever mounted on the upper face of said casing and arranged to limit the movement thereof in either direction, a pivoted keeper associated with said guide and adapted to hold said lever in position to effect engagement of said cams and rollers, and means for tripping said keeper to release the lever, 75 substantially as described.

HENRY AUGUST PREUSS.
